Patented Sept. 10, 1929.

UNITED STATES PATENT OFFICE.

THOMAS E. JAMISON, CHARLES CLIFFORD POLLARD, AND JAMES COLEMAN FARMER,
OF COLEMAN, TEXAS.

CLAMP.

Application filed October 9, 1928. Serial No. 311,310.

The present invention relates to improvements in cord or rope holders and has reference more particularly to a clamp for securing a wire line in any adjusted position, means being provided for preventing the cable from slipping when a weight is attached to the lower end of said cable.

A further object is to provide a cable clamp of the above mentioned character including a body provided with a downwardly tapered vertical opening through which the cable is disposed, a pair of wedge shaped clips being also arranged within the opening for cooperation therewith and for further engagement with the cable to positively secure the cable against slippage, means being provided for facilitating the raising of the cooperating slips to release the same from the cable, whereby the cable may be free to be moved through the clamp.

A further object is to provide a cable clamp of the above mentioned character which will, at all times, be positive and efficient in its operation, the same being further simple in construction, inexpensive, strong and durable and further well adapted to the purpose for which it is designed.

Other objects and advantages will become apparent as the nature of the invention proceeds and when taken in connection with the accompanying drawings.

In the accompanying drawings:

Figure 1 is a side elevation of the cable clamp embodying our invention.

Figure 2 is a similar view showing the side plates removed and also disclosing the manner in which the wedge shaped slips engage with the cable and the respective sides of the tapered opening formed in the body of the clamp.

Figure 3 is an edge elevation of the clamp for more clearly disclosing the pivoted yoke for manually raising the slips in the body, and

Figure 4 is a top plan view of the clamp. In the drawings, wherein for the purpose of illustration is shown the preferred embodiment of our invention, the numeral 1 designates a substantially rectangular shaped body, the same being formed with

a downwardly tapered vertical opening 2 that extends for the full length of the body and as is clearly shown in the drawings, said opening has communication with the front side of the body to facilitate the disposition of the clamp around the wire line or cable A. The opposed tapered sides 3 of the opening 2 are flat to provide opposed faces, upon which are slidable the complementary slips 4 and 5 respectively.

Each of these slips is of wedge shaped formation, and the outer edge of each slip is adapted for slidable engagement with the respective flat face 3 of the tapered opening 2 and for guiding the slips along the flat faces 3, said outer side edges of the slips are formed with guide ribs 6, the body portion 1 being formed with longitudinally extending grooves 7 to accommodate the ribs on the inner side of a slip as clearly illustrated in Figure 4.

A pair of plates 8 and 9 respectively are detachably secured on the front side of the body 1, by suitable securing bolts 10, said front side of the body being formed to accommodate the plate, and a retaining flange 11 is formed along each side edge of the front portion of the body for engagement with the outer side edges of the respective plates in the manner as clearly shown in Figures 1 and 4. The inner opposed longitudinal edges of the plates are spaced with respect to each other, to facilitate the proper positioning of the clamp around the cable A. The sliding slips 4 and 5 have their inner opposed longitudinal edge portions formed with complementary cable engaging grooves 12 and 13 respectively.

Apertured ears 14 are formed on the respective sides of the body at the upper end thereof for receiving the hooked end 15 of a substantially inverted U-shaped suspension bail 16, said hooks being formed on the free ends of the arms of this bail.

The invention further comprehends the shaped slips upwardly in the tapered opening provision of means for raising the wedge 2, in order to permit a new grip to be obtained upon the cable, and to this end

there is provided a yoke member designated generally by the numeral 17.

This yoke is formed from a single strip of flat metal bent back upon itself to form 5 a handle 18 and a fork at the inner end of the handle, the furcations 19 straddling the opposite sides of the body 1 and being pivotally connected thereto at points inwardly of the free end of said furcations as shown 10 at 20. The free end portion of each furcation is formed with a longitudinally-extending slot 21, as clearly indicated in Figure 3.

The body 1 is formed in its opposite sides with the longitudinally-extending slots 22 15 that have communication with the tapered opening 2 and extending through the slotted ends of the furcations 19 of the yoke member and through the respective slots 22 formed in the sides of the body are the bolts 20 23, the inner ends thereof being secured within suitable openings provided therefor in the outer sides of the respective slips as indicated in Figure 2.

When the parts are arranged in the manner shown in Figure 3, it will be observed 25 that the yoke 17 is in such a position as to cause the wedge shaped slips 4 and 5 to have tight engagement with the cable A and thereby properly secure the same. Furthermore, the weight that is attached to the 30 lower end of the cable will urge the wedge shaped slips downwardly in the tapered openings to further secure the cable against slippage.

35 Whenever it is necessary to release the clamp from the cable or to obtain a new grip the handle 18 of the yoke member is swung downwardly whereupon the slotted ends of the furcations will cooperate with 40 the bolt 23, operable in the slots 22 to raise the respective slips upwardly in the tapered opening 2 away from the cable and as soon as the handle is released, said slips will, by 45 gravity, again move downwardly in the tapered opening to obtain a further grip upon the cable and positively secure the same in the clamp.

It will thus be seen from the foregoing 50 description that we have provided a cable clamp that will at all times be positive and efficient in carrying out the purposes for which it is designed.

Furthermore, the parts of the clamp are so arranged and constructed as to permit the 55 same to be readily and easily assembled or disassembled.

While we have shown the preferred embodiment of our invention, it is to be understood that various changes in the size, 60 shape and arrangement of parts may be resorted to, without departing from the spirit of the invention or the scope of the appended claim.

What we claim as new is:

65 A cable clamp of the class described com-

prising a body formed with a vertical opening that has communication with the front side of the body and which opening extends for the full length of said body, the opposed sides of the opening tapering 70 gradually downwardly and being formed with flat faces, complementary wedge shaped cable gripping slips arranged within the opening for sliding engagement along the flat faces, cover plates for retaining the slips 75 in the opening, said slips adapted to normally move downwardly in the tapered opening by gravity to grip the cable and secure the same, a suspension bail attached to the upper end of the body, and means for 80 manually raising the slips to an in-operative position out of gripping engagement with the cable, said means comprising a yoke, the furcations thereof being disposed on opposite sides of the body and pivotally secured 85 thereto at a point inwardly of the free ends of said furcations, the sides of the body being formed with longitudinally-extending slots, bolts attached to the respective slots and extending through said slots, the outer 90 ends of the bolts being connected to the free ends of the respective furcations, and a handle associated with the yoke.

In testimony whereof we affix our signatures.

THOMAS E. JAMISON.
